FLUID COMPRESSOR

Nicolas Herzmark, Paris, France

Application November 6, 1933, Serial No. 696,875
In Great Britain October 29, 1932

14 Claims. (Cl. 230—183)

This invention relates to fluid compressors of the two-stage type.

A principal object of the present invention is to cool the low-pressure cylinder by means of a forced blast. Another object is to supply the low-pressure cylinder of the compressor with fluid under forced pressure. A further object is to supply the forced blast by means of a blower or fan mounted on the compressor casing and operatively rotated by the crankshaft of the compressor. Other objects will hereinafter appear.

In the following description, the invention is described with reference to the annexed drawings, in which:—

Fig. 1 is an elevation, part section, of a vertical, two-stage compressor for fluids showing the blower mounted on the side of the compressor casing and directly driven by the crankshaft. Fig. 2 is a view similar to Fig. 1 but at right angles to the latter. Fig. 3 is an elevation of the compressor showing the housing removed from the blower. Fig. 4 is a diagram indicating the arrangement of an intermediate gearing between the blower and the crankshaft. Fig. 5 is a plan view of Fig. 3.

The casing 1 of the compressor is provided with a crankshaft 2 having a crankpin 3 and mounted in suitable bearings 4, 4 in the said casing. This crankshaft is rotated in any suitable manner. The casing 1 is provided with an upper ribbed portion 1a and with a lower ribbed portion 1b.

Upon the crank pin 3, I have shown mounted a cross-head frame 5 5¹ by means of a bush or die 6 with sliding engagement, said cross-head frame travelling in guiding contact with the inner walls 7 of the casing 1. This cross-head frame here comprises an upper member 5 and a lower member 5¹ secured thereto as by the studs 5a. The piston 8 of the low-pressure cylinder 9 located inside the casing, is made integral with the upper member 5 and reciprocates in the cylinder 9 the latter being formed as a liner in the upper casing 1a. As shown, piston 8 has a stem 8¹ flanged at 8a, said flange being bolted to the member 5. A space forming an air-jacket 10 is left between the upper portion 1a of the casing and the exterior of the cylinder 9. This upper portion 1a thus forms an external wall surrounding cylinder 9. The piston 8 moves up and down in its cylinder 9 by reason of the rotation of the crankshaft 2 and its pin 3, the bush 6 moving transversely of the frame 5 5¹.

By means of this sliding-die engagement with the crank pin 3, and the travel of the outer walls of the frame 5 5¹ in the guiding inner walls 7, 7, the reciprocating movements of the piston 8 in its cylinder 9 are steadied.

The cylinder 9 is shown provided in its head 9b with an unloader valve 11 and with an outlet

valve 12 leading to pipe 13 outside the casing 1. The spring 11¹ bears on the collar-fitted stem 11b of valve 11 and normally holds valve 11 on its seat 11a, and the outlet valve 12 is shown as a ball valve, the lift of which ball can be limited by a screw 12a.

The cross-head frame 5, 5¹ is also provided integrally with a dependent piston 14 working in a fixed cylinder 15 upstanding from the base of the casing and extending into the portion 1b. The head or closed end of this cylinder is provided with an inlet valve 16 and an outlet valve 17. These valves 16 and 17 are fitted with springs 16a and 17a respectively to hold them on their seatings. The aforesaid external pipe 13 extends to below the inlet valve 16 and is connected therewith by passage 16¹. The outlet valve leads to the pressure supply pipe 17¹. The bottom 1b of the casing is provided with a sump 1c for oil which surrounds the cylinder 15 for part of its height.

Air inlets 18, 18 are provided in the wall of the upper or low-pressure cylinder and so located that when the piston 8 uncovers these inlets, air can pass in to the space above the piston 8. These air inlets are supplied from the air jacket 10 which extends around the cylinder 9.

Air is supplied to this air-jacket 10 through a transfer port or supply port 19 extending through the casing 1a and in communication with the discharge outlet from a rotary blower or fan.

In Fig. 1, the hub 20 of the rotary blower 21 is directly mounted upon the crankshaft 2 so as to rotate therewith, the blower being encased in a housing 22 suitably secured as by bolts 23 to the compressor casing 1. This blower is shown as of the centrifugal type with an axial air inlet and a discharge outlet 24 which latter delivers a forced blast to the supply port or transfer port 19 and so to the air-jacket 10. An outlet port 25 from the air-jacket through the upper part of the casing 1a leads to atmosphere. The air under pressure from the blower outlet 24 is thus admitted through transfer port 19 to the air-jacket and after cooling the cylinder 9 escapes through the outlet port 25. This outlet port is with advantage diametrically in line with and remote from the transfer port 19 and it is preferably at a higher level in the wall of the casing 1a than the transfer port 19.

In Fig. 1, the air blast from the blower 21 is shown divided, a portion travelling around the air-jacket 10, and passing out therefrom through outlet port 25. The other portion of the air under pressure from the blower 21 passes from the port 19 and air-jacket 10 into the low-pressure cylinder 9 above the piston 8 when that piston in its descent has uncovered the inlet ports 13, 18 in cylinder 9.

The whole supply of air from the blower 21

120

when the inlet ports 18 are covered by piston 8, will circulate around the air-jacket 10 for the cylinder 9 and escape through the outlet 25.

Obviously two or more of these outlet ports 25 may be provided at intervals around the upper portion of casing 1a adjacent to the air-jacket 10.

By means of this air under pressure from the blower 21 directly operated from the crankshaft 2, the low-pressure cylinder 9 is most effectively 10 cooled and, moreover, air can be forced under pressure into the interior of cylinder 9.

The air compressed in cylinder 9 is thereafter transferred through valve 12, pipe 13 and inlet valve 16 to the high-pressure cylinder 15 on the 15 other side of the crankshaft 2, and after further compression in that cylinder by piston 14, is discharged through valve 17 into pressure supply pipe 17¹ and the container hereafter mentioned.

The casing 1 is provided at its upper and lower 20 extremities with end-plates 1d, 1e which are shaped with towers or bosses 1f to enclose the valves 11, 16 and 17, and these end plates are bolted or otherwise secured to the casing of the compressor.

25 In Fig. 1, I have shown one of the bearings 4 for the crankshaft 2 recessed into the housing 22, and I have also shown the hub 20 suitably secured upon the end of the crankshaft 2 by means of a disc 26 and a set screw 27.

30 In the modification of Fig. 4, an intermediate gear is provided between the crankshaft 2 and the bladed fan. The hub 20 is here shown provided with arms 20¹ carrying toothed pinions 29 by means of screws 28 passing into said arms; these pinions are, for example, three in number and mesh with a single driving pinion 30 fixed upon the crankshaft (so as to rotate therewith) and also with an internally toothed ring 31 secured to the housing 22 by means of screws 32. 35 The rotation of the crankshaft 2 causes the blower to revolve but the speed of rotation of the blower will be less than that of the crankshaft. The blower housing is mounted on the compressor casing and operated by the rotating crankshaft, 40 as in the previous example, but in an indirect manner.

An external pipe 34 extends from the passage 34¹ and pressure supply pipe 17¹ to above the stem 11b of the cut-off valve 11 by means of 50 passage 35 in the casing, and passage 36 in tower 1f for the purpose which will now be described. The fluid compressed in this two-stage compressor passes from the supply-pipe 17¹ to a container 37 through a pipe 38. This container 37 is provided 55 with a bath of oil indicated at 39 and the pipe 38 delivers to below the level of the oil. When the pressure in the container above the oil reaches a predetermined degree, oil is forced back along the pipe 38 to pipes 17¹ and 34, to passages 35 and 36 and to above the cut-off valve 11. This oil under pressure opens the valve 11 and allows the piston 8 to work idly, the air from cylinder 9 escaping, when the cut-out valve 11 is thus held open, through ports 40 to the atmosphere.

60 The proportions between the low-pressure cylinder 9 and the high-pressure cylinder 15 of this vertical two-stage compressor may be as desired but, for example, they may be as 5:2.

What I claim is:—

70 1. In a vertical two-stage fluid compressor having low-pressure and high-pressure cylinders arranged respectively above and below a rotatable crankshaft journaled in the casing of the compressor, the combination with an air-jacket provided between the exterior of the low-pressure

cylinder and the casing of the compressor, of means for admitting air from said air-jacket to the interior of said low-pressure cylinder, of a supply port to said air-jacket and an outlet port from said air-jacket, and of means operated by said crankshaft for forcing air under pressure into said air-jacket by way of said supply port, said means being mounted on the casing of said compressor.

2. In a vertical two-stage fluid compressor of the character described, in combination, a casing for the compressor, a rotatable crankshaft journaled in said casing, valve fitted low pressure and high pressure cylinders arranged respectively above and below said rotatable crank-shaft, an air-jacket interposed between the exterior of said low pressure cylinder and said casing, inlet ports leading from said casing to the interior of said low pressure cylinder and connected together by said air-jacket, a transfer port leading from the external surface of said air-jacket to the space within said air-jacket, an outlet port leading from said air-jacket to the exterior of said low pressure cylinder, a piston in each of said cylinders, actuating means for said pistons, said actuating means being provided within said casing, and rotatable means operated by said crankshaft for forcing air under pressure into said air-jacket, said rotatable means being mounted on the exterior of said compressor.

3. In a vertical two-stage fluid compressor, having low-pressure and high-pressure cylinders arranged respectively above and below a rotatable crankshaft, an air-jacket for said low-pressure cylinder, said air-jacket formed by a wall surrounding the low-pressure cylinder but spaced therefrom, a transfer port through said wall into the said air-jacket, an outlet port from said air-jacket through said wall, and a rotary blower mounted on the compressor and operated by said crankshaft, said blower having a discharge outlet leading to said transfer port.

4. In a vertical two-stage air compressor of the type described, having low-pressure and high-pressure cylinders arranged respectively above and below a rotatable crankshaft mounted in the casing of the compressor, said low-pressure cylinder having air intake ports, the combination with a passage connecting said air intake ports and having also a transfer port, of a rotary blower mounted upon the compressor and operated by said crankshaft, said blower having an air discharge outlet communicating with said connecting passage through said transfer port.

5. In a vertical two-stage compressor of the type described, having a low-pressure cylinder arranged above a rotatable crankshaft mounted in the casing of the compressor, said low-pressure cylinder having air intake ports, the combination with a passage extending wholly around said low-pressure cylinder to form an air-jacket therefor and connecting said air intake ports, of an outlet port from said air-jacket and a transfer port leading to said air-jacket, and of a rotary blower mounted on said compressor and operated by said crankshaft, said blower having an air discharge outlet communicating with said transfer port.

6. In a vertical two-stage compressor of the type described, having low-pressure and high-pressure cylinders arranged respectively above and below a rotatable crankshaft mounted in the casing of the compressor, the combination with a passage connecting the air intake ports for the low-pressure cylinder, said passage extending around said low-pressure cylinder and having

- also an outlet port, said outlet port being on the side of the low-pressure cylinder remote from said transfer port and at a level higher than said transfer port, of a rotary blower mounted upon 5 the casing of the compressor and operated by said crankshaft, said blower having an air discharge outlet communicating with said connecting passage by way of said transfer port.
7. In a vertical two-stage air compressor of 10 the character described and having valve-fitted low-pressure and high-pressure cylinders arranged respectively above and below a rotatable crankshaft journaled in the casing of the compressor, the combination with a passage connecting 15 the air intake ports for the low-pressure cylinder, which passage extends around said low-pressure cylinder and has also an outlet port, said outlet port being on the side of the low-pressure cylinder remote from said transfer port 20 and at a level higher than said transfer port, of a rotary blower operated by said crankshaft, said blower having a housing secured to the casing of the compressor and a hub secured to said crankshaft so as to rotate therewith, and said blower 25 having its discharge outlet in direct communication with said transfer port.
8. In a vertical two-stage air compressor of 30 the character described and having low-pressure and high-pressure cylinders arranged respectively above and below a rotatable crankshaft journaled in the casing of the compressor, the combination with an air-jacket formed around the low-pressure cylinder, of air intake ports for the low-pressure cylinder, said intake ports being 35 supplied from said air-jacket and said air-jacket having also an outlet port on the side of the low-pressure cylinder remote from said transfer port and at a level higher than said transfer port, of a hub-fitted rotary blower mounted co- 40 axially with said crankshaft and operated by said crankshaft said blower having its discharge outlet in communication with said transfer port, and of gearing arranged between said blower and said rotatable crankshaft.
- 45 9. In a vertical two-stage air compressor of the character described, having low-pressure and high-pressure cylinders arranged relatively above and below a rotatable crankshaft journaled in the casing of the compressor with air intake 50 ports for the low-pressure cylinder, the combination with a passage connecting the said air intake ports and extending around said low-pressure cylinder to form an air-jacket therefor and having an outlet port on the side of the low-pressure cylinder remote from said transfer port 55 and at a level higher than said transfer port, of a rotary blower having a housing secured to the casing of the compressor, said blower having its discharge outlet in communication with said 60 transfer port, and of toothed gearing interposed between said blower and said rotatable crankshaft.
10. A fluid compressor comprising a casing, a 65 crankshaft journaled in said casing, means for rotating said crankshaft, said crankshaft including a crank pin, a cross-head frame adapted to be reciprocated in said guides, a bush in said cross-head frame adapted to travel across said frame, said bushing being mounted on said crank 70 pin, a piston secured to said cross-head frame and extending above said crankshaft, guides in said casing for said cross-head frame, a low-pressure cylinder mounted in the casing and co- 75 acting with said piston, a member dependent from said cross-head frame, a stationary member up-
- standing from the base of the casing, said dependent member cooperating with said stationary member to form a high-pressure cylinder, an air-jacket between said low-pressure cylinder and said casing, a transfer port through said casing and leading to said air-jacket, an outlet from said air-jacket, and a centrifugal blower driven by said crankshaft, said blower having a discharge outlet communicating with said air-jacket through said transfer port.
11. In a vertical two-stage fluid compressor of 80 the character described and having low-pressure and high-pressure cylinders arranged respectively above and below a rotatable crankshaft journaled in the casing of the compressor, the combination with an air-jacket provided between the exterior of the low-pressure cylinder and a wall forming part of the said casing, of inlet ports leading from the exterior surface of said casing to the interior of said low-pressure cylinder and connected together by said air-jacket, a transfer port leading from the external surface of said air-jacket to the space within said air-jacket and an outlet port leading from said air-jacket to the exterior of said casing, guiding means for the 85 pistons of said low-pressure and high-pressure cylinders, said guiding means being provided within the said casing, and rotatable means operated by said crankshaft for forcing air under pressure into said air-jacket, said rotatable means being mounted on the exterior of the said compressor.
12. In a two-stage fluid compressor having low-pressure and high-pressure cylinders arranged on either side of a rotatable crankshaft journaled in 90 the casing of the compressor, the combination with an air-jacket provided between the exterior of the low-pressure cylinder and the casing of the compressor, of means for admitting air from said air-jacket to the interior of said low-pressure cylinder, a supply port to said air-jacket and an outlet port from said air-jacket and means operated by said crankshaft for forcing air under pressure into said air-jacket by way of said supply port, said means being mounted on the casing of 95 the compressor.
13. In a two-stage fluid compressor having low-pressure and high-pressure cylinders arranged on either side of a rotatable crankshaft journaled in 100 the casing of the compressor, the combination with an air-jacket provided between the exterior of the low-pressure cylinder and the casing of the compressor, of means for admitting air from said air-jacket to the interior of said low-pressure cylinder, a supply port to said air-jacket, an outlet port from said air-jacket and means operated by said crankshaft for forcing air under pressure into said air-jacket by way of said supply port, said means being mounted on the casing of 105 the compressor.
14. In a two-stage fluid compressor having low-pressure and high-pressure cylinders arranged on either side of a rotatable crankshaft journaled in 110 the casing of the compressor, the combination with an air-jacket provided between the exterior of the low-pressure cylinder and the casing of the compressor, of means for admitting air from said air-jacket to the interior of said low-pressure cylinder, a supply port to said air-jacket and an outlet port from said air-jacket and means operated by said crankshaft for forcing air under pressure into said air-jacket by way of said supply port, said means being mounted on the casing of 115 the compressor.
15. In a two-stage fluid compressor having low-pressure and high-pressure cylinders arranged on either side of a rotatable crankshaft journaled in 120 the casing of the compressor, the combination with an air-jacket provided between the exterior of the low-pressure cylinder and the casing of the compressor, of means for admitting air from said air-jacket to the interior of said low-pressure cylinder, a supply port to said air-jacket, an outlet port from said air-jacket and means operated by said crankshaft for forcing air under pressure into said air-jacket by way of said supply port.
16. In a two-stage fluid compressor having low-pressure and high-pressure cylinders arranged on either side of a rotatable crankshaft journaled in 125 the casing of the compressor, the combination with an air-jacket provided between the exterior of the low-pressure cylinder and the casing of the compressor, of means for admitting air from said air-jacket to the interior of said low-pressure cylinder, a supply port to said air-jacket, an outlet port from said air-jacket and means operated by said crankshaft for forcing air under pressure into said air-jacket by way of said supply port.
17. In a two-stage fluid compressor having low-pressure and high-pressure cylinders arranged on either side of a rotatable crankshaft journaled in 130 the casing of the compressor, the combination with an air-jacket provided between the exterior of the low-pressure cylinder and the casing of the compressor, of means for admitting air from said air-jacket to the interior of said low-pressure cylinder, a supply port to said air-jacket, an outlet port from said air-jacket and means operated by said crankshaft for forcing air under pressure into said air-jacket by way of said supply port.
18. In a two-stage fluid compressor having low-pressure and high-pressure cylinders arranged on either side of a rotatable crankshaft journaled in 135 the casing of the compressor, the combination with an air-jacket provided between the exterior of the low-pressure cylinder and the casing of the compressor, of means for admitting air from said air-jacket to the interior of said low-pressure cylinder, a supply port to said air-jacket, an outlet port from said air-jacket and means operated by said crankshaft for forcing air under pressure into said air-jacket by way of said supply port.
19. In a two-stage fluid compressor having low-pressure and high-pressure cylinders arranged on either side of a rotatable crankshaft journaled in 140 the casing of the compressor, the combination with an air-jacket provided between the exterior of the low-pressure cylinder and the casing of the compressor, of means for admitting air from said air-jacket to the interior of said low-pressure cylinder, a supply port to said air-jacket, an outlet port from said air-jacket and means operated by said crankshaft for forcing air under pressure into said air-jacket by way of said supply port.
20. In a two-stage fluid compressor having low-pressure and high-pressure cylinders arranged on either side of a rotatable crankshaft journaled in 145 the casing of the compressor, the combination with an air-jacket provided between the exterior of the low-pressure cylinder and the casing of the compressor, of means for admitting air from said air-jacket to the interior of said low-pressure cylinder, a supply port to said air-jacket, an outlet port from said air-jacket and means operated by said crankshaft for forcing air under pressure into the work chamber of the compressor.
